(57) **CLAIM**

The ornamental design for a utensil rest, as shown and described.

DESCRIPTION

FIG. 1 is a front perspective view of a utensil rest, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The utensil rest has been shown with symbolic breaks. The appearance of any portion of the article between the break lines forms no part of the claimed design.

The broken lines in the figures illustrate the portions of the design that form no part of the claimed design.

1 Claim, 5 Drawing Sheets
